UNITED STATES PATENT OFFICE.

WILLIAM C. FOULDS, OF TUCKERTON, NEW JERSEY.

INDICATOR FOR INJECTOR PRESSURE KIERS.

Application filed November 12, 1921. Serial No. 514,839.

To all whom it may concern:

Be it known that I, WILLIAM C. FOULDS, a citizen of the United States, residing at Tuckerton, in the county of Ocean, State of New Jersey, have invented a new and useful Indicator for Injector Pressure Kiers, of which the following is a specification.

In injector kiers of the conventional type, which are usually constructed for quantities of cloth or yarn varying from six hundred to four thousand pounds, in order to attain the best results in practice, I have found it to be essential that the height or top level of the yarn or other material to be treated in the kier be maintained at a certain position with respect to or above the water level or height of the liquor within the kier.

These kiers are of somewhat massive construction and after the yarn or other material has been placed therein for treatment and the kier closed, (while it has been possible to ascertain the height of the water level from a suitable water gauge) it has heretofore been impossible to ascertain accurately the height of the top surface of the yarn, which is being treated with respect to the water level.

To obviate the foregoing disadvantages, I have devised a simple form of indicating device which can be readily applied to existing kiers, whereby the height or level of the yarn or other material within the kier can be readily ascertained, so that the height of the water level or the top of the liquor within the kier can be correspondingly regulated in order to give the best results, provision being also made for properly packing the opening in the top of the kier through which the indicator passes, so that the interior of the kier will be tight and there will be no escape of the steam or pressure therein.

My invention in its broad aspect is capable of application to any standard or conventional pressure kier and, in the present instance, I have shown it applied to what is usually termed an injector pressure kier, wherein the circulation of the liquid is effected by means of a steam ejector, the steam passing down to the bottom of the kier and through an ejector drawing the liquid through a pipe from beneath the false bottom of the kier and forcing it to the top thereof through an upright pipe which con-

veyes it through a nozzle back into the kier again, the water and liquid being supplied to the kier in proper proportions and any waste being withdrawn from the kier according to requirements.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

The figure represents a sectional view of my novel indicator device for an injector kier or the like, embodying my invention.

In carrying out my invention, which is applicable to any standard construction of pressure kier or injector kier 1, constructed of the body 2, bottom 3, top or dome 4, and false bottom 5, provided with the steam inlet pipe 6, injector 7, upwardly extending pipe 8, leading to the head or nozzle 9, in which water and liquor are received from the pipes 10 and 11 respectively, I provide the top 4 with a stuffing box 12, through which passes the gauge rod or indicator 13, having the bottom plate or foot 14, which may be weighted if desired, and rests on the yarn or material to be treated and the knob or handle 15 at its upper end. The rod or indicator 13 has thereon suitable graduations or indicating means, whereby the height of the yarn or other material 16 contained in the kier can be readily determined, with respect to the water level indicated by the line 17, the height of which at all times being readily ascertained by the water gauge 18, which may be of any conventional type. The kier is further provided with the bottom outlet 19, leading to the pipe 20, communicating with the injector 7 and having the valve 21 therein, from which the pipe 22 leads to the drain 23, said valve being operated by the handle 24 on the upper end of the valve rod 25, said handle being readily accessible from the working floor 26.

The operation is as follows:—

Liquor and water are introduced through the pipes 11 and 10 into the nozzle 9, and

commingled with the steam and liquid forced upwardly through, the pipe 8 by the injector 7 and its adjuncts. The water level indicated by the line 17, can be readily ascertained by the water gauge 18 and the top of the yarn or other material can be ascertained by the graduations on the indicator or rod 13, and as it is desirable that the top of said yarn be maintained at a certain predetermined point above the level 17, this can be readily effected by regulating the supply of liquid to the kier or by withdrawing the liquid through the drains 22 and 23. The stuffing box 12 effectively packs the opening in the top 4 and by my novel collocation of the indicator rod, with the water gauge, in a kier of the character described, I have produced a very efficient device for the purpose intended, and one which is greatly superior to the kiers now commonly in vogue.

It will now be apparent that I have devised a novel and useful indicator for injector pressure kiers, which embodies the features of advantage enumerated as desirable in the statement of the invention and the above description, and while I have in the present instance shown and described a preferred embodiment thereof which will give in practice satisfactory and reliable results, it is to be

understood that the same is susceptible of modification in various particulars without departing from the spirit or scope of the invention or sacrificing any of its advantages.

Having thus described my invention, what I claim as new and desire to secure by Letters Patent, is:—

1. The combination with a pressure kier having a gauge for indicating the level of liquid therein, of a vertically disposed slideable indicating rod passing through the top of the kier to indicate above the top of the latter the height of the material contained in the kier, the foot of said rod resting on said material, whereby the height of the material may be compared with the height of the liquid.

2. In an injector pressure kier having a top provided with a stuffing box, a vertically slideable indicator rod movable in said stuffing box and provided with graduations thereon, the foot of said rod being adapted to contact with the top of the material being treated in the kier, and a liquid indicator gauge located at the upper portion of said kier, whereby the height of the liquid and the height of the material can be compared.

WILLIAM C. FOULDS.
